UNITED STATES PATENT OFFICE.

EDGAR TAYLOR, OF YONKERS, NEW YORK.

BROODER.

1,141,853.

Specification of Letters Patent. Patented June 1, 1915.

Application filed April 17, 1912. Serial No. 691,311.

To all whom it may concern:

Be it known that I, EDGAR TAYLOR, a citizen of the United States, residing at Yonkers, in the county of Westchester and State of New York, have invented new and useful Improvements in Brooders, of which the following is a specification.

The present invention provides a structure intended chiefly for keeping the chicks at a uniform given temperature during the period of brooding, thereby insuring a full brood from a given number of fertile eggs.

The invention provides a brooder which may be located in the open with perfect safety as against climatic changes and conditions and which will prevent chilling of the chicks or an overheating thereof, both of which would prove fatal to the maturing of the hatching.

The invention provides a novel form of inclosing structure and peculiar heating means, the latter being of such formation as to insure a uniform temperature and the consumption of a minimum amount of oil, the heater being in the nature of a lamp and embodying a boiler for equalizing the temperature in the structure receiving the eggs to be hatched.

The invention consists of the novel features, details of construction and combination of parts, which hereinafter will be more particularly set forth, illustrated in the accompanying drawings, and pointed out in the appended claim.

Referring to the drawings, forming a part of the specification, Figure 1 is a perspective view of a brooder embodying the invention. Fig. 2 is a vertical section. Fig. 3 is a detail view of the lamp and lamp supporting means, showing the parts on a larger scale. Fig. 4 is a detail view, showing the means for regulating the supply of air to the lamp. Fig. 5 is an enlarged detail section of the relief valve.

Corresponding and like parts are referred to in the following description, and indicated in all the views of the drawings, by the same reference characters.

The body of the brooder is indicated at 1 and is of box form, being permanently closed at its bottom and sides and closed at its top by means of a cover 2, which is removable to admit of access being had to the interior of the brooder. The cover 2 slants so as to shed moisture. The parts forming the inclosing walls are formed of wood

which is covered by means of asbestos and sheet metal, the latter being on the outside so as to render the structure both fire and weather proof. A door 3 closes an opening formed in a side of the body and is provided with a window to admit of the interior of the incubator being observed at all times. One or more ventilating openings 4 are formed in a side of the body in convenient position to attain the best results. The interior of the structure is lined with a fabric, such as flannel. A tray 5 is supported within the brooder some distance above the bottom thereof and is designed to serve as a hover. The tray 5 may be constructed of any material and is lined upon its under side with flannel or other textile.

The heating mechanism embodies a lamp 6, which by preference is located below the bottom of the structure so as to be readily accessible without requiring the cover of the brooder or the door 3 thereof to be opened. The body of the lamp 6 is surrounded by means of a jacket 7, which is designed to receive a quantity of water, thereby preventing overheating of the lamp. A casing 8 is suspended from the bottom of the brooder and receives the lamp 6, said casing being of sheet metal and having an opening 9 in its bottom for the admission of air, which supports combustion and also assists in preventing overheating of the lamp. A stand 10 is located upon the bottom of the casing 8 and consists of a plate and feet, the latter resting upon the bottom of the casing and supporting the plate the required distance above the opening 9. A door 11 closes an opening formed in a side of the casing 8 and has a window to admit of observing the light so that the lamp may be regulated to meet existing conditions. A cut-off 12 is adapted to regulate the effective size of the opening 9 to control the admission of air so that in windy weather the opening 9 may be partly closed and in calm weather uncovered to its full extent. The cut-off 12 is pivoted at one end to the bottom of the casing and is provided with an extension 13 forming a finger piece to be grasped when it is required to manipulate the cut-off. The cut-off 12 is in the nature of a plate and has an opening, thereby preventing choking of the lamp by cutting off the air thereto should the cut-off perchance be moved so as to extend over the opening 9.

A boiler 14 is located within the body of

the incubator and is placed upon the bottom or floor thereof. The boiler 14 has a central flue 15 which is tapered throughout its length and extends above the top of the 5 boiler and the cover 2. An opening is formed in the bottom of the incubator and registers with the central flue 15 and with the chimney of the lamp 6 so that the hot air and fumes from the lamp may escape 10 and at the same time serve to heat the water in the boiler 14 as a result of the hot air and gases coming in contact with the walls of the said flue 15. A tube 16 connects with the top of the boiler 14 and extends upwardly through the cover 2, said tube providing means for filling the boiler with water and also providing for escape of steam, thereby preventing dangerous internal pressure. The tube 16 may be provided 15 with a valve of any construction for closing the same and which will admit of any steam generated readily escaping. Short pipes or collars are fitted to the cover 2 in line with the openings through which the 20 flue 15 and tube 16 extend and are secured to the cover in any manner. A guard 17 surrounds the boiler and is spaced therefrom a distance to prevent the chicks from coming in contact with the boiler and meeting 25 with injury. This guard consists of a wire screen which is of cylindrical form and is placed upon the floor of the brooder. The eggs to be hatched are placed on the 30 trays 5, after which the cover 2 is closed upon the body of the brooder. The boiler 14 is supplied with water and when the lamp 6 is lighted the water in the boiler is heated and the heat thus generated is radiated and warms the interior of the 35 brooder. The heat from the lamp is transmitted through the body of the water contained in the boiler into the body of the structure, thereby warming the atmosphere thereof so as to keep the eggs placed upon 40 the floor 5 at the proper temperature for incubation. The heat in its passage through the water of the boiler is tempered to such an extent as to prevent the overheating of the brooder. In extreme cold weather the 45 lamp is turned to produce a larger flame than in mild weather when the flame is re-

duced. The lining of the inclosing parts of the structure and the covering of said parts on the exterior prevents the cold from striking through and insures a practically uniform temperature. It is noted that the brooder is mounted upon legs 18, thereby supporting the body a distance from the ground when the latter is placed in the open. 55

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claim appended hereto. 60

The trays 5 act as hovers for the chicks 75 and serve to distribute and equalize the heat, the bottom being of flannel giving the best results.

Having thus described the invention what is claimed as new, is:—

An incubator heater comprising a combustion chamber supported thereby, a metallic cylindrical boiler superimposed above said chamber and adapted to contain a quantity of water, a tapering flue centrally mounted in said boiler and opening into said combustion chamber at its large end and into the atmosphere at its small end, a fibrous sheeting spaced above the bottom of the incubator, and a cylindrical wire mesh guard encircling said boiler and having its edges contacting with the under surface of the fibrous sheeting and the top surface of the bottom of the incubator respectively. 80 85 90 95

In testimony whereof I affix my signature in presence of witnesses:

EDGAR TAYLOR.
